(57) **CLAIM**

The ornamental design for a combined business card with bar code, laser punched holes and radio frequency IC, as shown and described.

DESCRIPTION

FIG. 1 is a perspective view of a combined business card with bar code and laser punched holes and radio frequency IC in a fully closed position showing my new design; FIG. 2 is a front elevational view thereof; FIG. 3 is a right side elevational view thereof; FIG. 4 is a left side elevational view thereof; FIG. 5 is a bottom plan view thereof; FIG. 6 is a top plan view thereof; FIG. 7 is a rear elevational view thereof; FIG. 8 is a perspective view of FIG. 7 thereof; FIG. 9 is an enlarged cross-sectional view taken along lines 9—9 of FIG. 2 thereof; FIG. 10 is an enlarged cross-sectional view taken along lines 10—10 of FIG. 2 thereof; FIG. 11 is an enlarged fragmentary cross-sectional view taken along lines 11—11 of FIG. 7 thereof; FIG. 12 is a perspective view of the combined business card with bar code and laser punched holes and radio frequency IC in a partially opened position thereof; FIG. 13 is a perspective view of the combined business card with bar code and laser punched holes and radio frequency IC in a fully opened position thereof; FIG. 14 is a front elevational view of FIG. 13 thereof; FIG. 15 is a right elevational view thereof; FIG. 16 is a left elevational view thereof; FIG. 17 is a bottom plan view thereof; FIG. 18 is a top plan view thereof; FIG. 19 is a rear elevational view thereof; FIG. 20 is a perspective view of FIG. 19 thereof;

FIG. 21 is a second embodiment of rear elevation view FIG. 19 thereof, it being understood that the undisclosed front, right-side, left-side, bottom and top views are the same as in FIG. 14–18; and,

FIG. 22 is a perspective view of FIG. 21.

Broken lines showing letterings and numerals in FIG. 1, FIG. 2, FIG. 12–14, and FIG. 19–22 are for illustrative purposes only and form no part of the claimed design.

The broken lines bisecting the design horizontally in the middle in FIGS. 13–14 and FIGS. 19 to 22 has been employed to depict a scored fold line.
